UNITED STATES PATENT OFFICE.

GEORGE O. DRAPER, OF HOPEDALE, MASSACHUSETTS, ASSIGNOR TO THE DRAPER COMPANY, OF SAME PLACE AND PORTLAND, MAINE.

SPINNING APPARATUS.

SPECIFICATION forming part of Letters Patent No. 651,702, dated June 12, 1900.

Application filed October 23, 1899. Serial No. 734,428. (No model.)

To all whom it may concern:

Be it known that I, GEORGE O. DRAPER, of Hopedale, county of Worcester, State of Massachusetts, have invented an Improvement in 5 Spinning Apparatus, of which the following description, in connection with the accompanying drawings, is a specification, like letters on the drawings representing like parts.

This invention has for its object the production of simple, cheap, and efficient spinning apparatus belonging in general to the "dead-spindle" type, although in many particulars my invention differs therefrom, as will appear more fully hereinafter.

15 In the apparatus forming the subject-matter of this invention the bobbin, or "yarn-carrier," as I shall term it, is rotatable directly upon the dead-spindle and is frictionally connected with a whirl, the latter being 20 centered and carried by the yarn-carrier when the latter is in running position.

Figure 1 is a vertical sectional view of spinning apparatus embodying my invention, and Fig. 2 is a detail of a modification to be described.

Referring to Fig. 1, I have shown a holder B for the dead-spindle A, said holder having a threaded shank B' to enter a hole in the ordinary rail and receive a retaining-nut B^X, 30 whereby the holder and spindle are maintained in position on the rail. The hollow shank is shown as threaded interiorly at its lower end to receive an end support b^X, though obviously the shank could be formed with an 35 integral bottom. The lower end of the dead-spindle is shown as extended into the holder, and a suitable packing P may be interposed between the spindle and holder, if desired, to obviate any undesirable vibration which 40 might otherwise be set up in the spindle when rotating the yarn-carrier at high speeds, the friction of the packing preventing rotation of the spindle. Instead of a packing a bolster might be employed for the same purpose, as 45 shown at H, Fig. 2, fitting loosely into the holder B; but in either case the spindle is held from rotation in the holder. In using a bolster any one of many well-known devices could be used to prevent rotation of the bolster, such 50 as a pin on the holder engaging a notch in

the bolster, the spindle fitting tightly in the bolster.

A preferably metallic whirl D, shown as having a large downwardly-tapering bore and the usual hand-receiving groove d, has secured to it a wooden or other suitable fibrous collar d', said collar surrounding the dead-spindle A; but the bore d² of the collar is larger than the diameter of the spindle in order that the collar shall be out of contact therewith when in operation. As shown in Fig. 1, this collar rests upon an end bearing b², formed, conveniently, by an upturned portion of the holder B. A suitable guard g is mounted on the holder to project over a shoulder d^X on the whirl and prevent withdrawal thereof with the yarn-carrier.

The yarn-carrier C is made, preferably, of wood, with an exteriorly-tapered base c to enter and frictionally engage the tapered bore 70 of the whirl, the yarn-carrier having at its lower end a bearing portion c' to engage the spindle with a running fit, while the counter-bore c² has a wooden or fibrous bushing c³ inserted therein at its upper end to engage the 75 spindle also with a running fit. As herein shown, the upper bearing c³ engages a reduced portion a of the spindle. When the yarn-carrier is placed on the spindle, it is pushed down into the whirl and acts to center the 80 latter on the spindle, so that the collar d' is held from contact with the spindle, the whirl being carried by the yarn-carrier. When the yarn-carrier is removed, the whirl runs on the spindle by means of the collar d'. The 85 bearings c' and c³ and also the collar d' are soaked or thoroughly impregnated with an antifriction compound, and the wear is thus reduced to a minimum.

The use of oil is entirely obviated by the 90 construction shown, and the construction is at once simple and highly efficient, while the cost of production is very greatly reduced.

Having fully described my invention, what I claim, and desire to secure by Letters Patent, is—

1. A dead-spindle, a yarn-carrier having contained non-metallic bearings, to run directly upon the spindle, and a whirl loosely surrounding the spindle and adapted to be 100

engaged and centered by the yarn-carrier, and maintained thereby out of contact with the spindle.

2. A dead-spindle, and a whirl loosely surrounding it and provided with a non-metallic collar to bear upon the spindle when the yarn-carrier is removed.

3. A dead-spindle, a holder therefor, a whirl provided with a non-metallic collar loosely surrounding the spindle and having an end bearing on the holder, and a removable yarn-carrier adapted to run directly upon the spindle and to be frictionally engaged by the whirl.

15 4. A dead-spindle, a holder in which it is yieldingly mounted, a whirl, and a removable yarn-carrier having contained non-me-

tallic bearings to directly engage and run upon the spindle.

5. A dead-spindle, a whirl having a tapered bore, a non-metallic collar attached to the whirl and having a bore larger than the spindle, and a removable yarn-carrier having a tapered base to frictionally engage the bore of the whirl, the yarn-carrier centering the whirl and maintaining its collar from engagement with the spindle.

In testimony whereof I have signed my name to this specification in the presence of two subscribing witnesses.

GEORGE O. DRAPER.
